(57) **CLAIM**

The ornamental design for a Greek key carpet holder, as shown and described.

DESCRIPTION

FIG. 1 is a front elevational view of a greek key carpet holder showing my new design;

FIG. 2 is a rear elevational view thereof;

FIG. 3 is a left side elevational view thereof; the right side elevational view being a mirror image;

FIG. 4 is a top plan view thereof; and,

FIG. 5 is a bottom plan view thereof.

The broken lines shown in FIGS. 1-5 are for illustrative purposes only and form no part of the claimed design.
